UNITED STATES PATENT OFFICE.

MORRIS STANGER, OF BROOKLYN, NEW YORK.

VEST.

1,250,693.

Specification of Letters Patent. Patented Dec. 18, 1917.

Application filed November 10, 1916, Serial No. 130,547. Renewed November 15, 1917. Serial No. 202,244.

To all whom it may concern:

Be it known that I, MORRIS STANGER, a citizen of the United States, and a resident of the city of New York, borough of Brooklyn, in the county of Kings and State of New York, have invented a new and Improved Vest, of which the following is a full, clear, and exact description.

This invention relates to chest protectors, 10 bandages or the like and has particular reference to an improved construction of protecting means adapted especially to prevent congestion of the lungs or pneumonia or the recurrence of such a malady.

15 Among the objects of the invention is to provide a sort of garment or bandage adapted to be worn around the chest somewhat in the nature of a vest or jacket, the same being provided with one or more plies of material including a ply of material impervious 20 to air or water.

Another object of the invention is to provide a device of the nature set forth adapted to be worn by an individual of either sex 25 and of any age.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like 30 reference characters designate the same parts in the several views, and in which—

Figure 1 is a front elevation of a vest made in accordance with this invention, indicating a preferred embodiment thereof, a 40 portion of the front being shown broken away to disclose hidden parts: and

Fig. 2 is a vertical sectional detail on the line 2—2 of Fig. 1.

Referring now more particularly to the 45 drawings, I show a vest or bandage having front panels 10 and 11 and a back 12. Any

suitable design of device may be provided for the neck 13 and form armholes at 14.

A strip or ply of lining material of any suitable nature is indicated at 15 and adjacent to the outer surface of the lining is arranged a mass of fibrous padding 16 of wool, 50 felt, cotton or the like extending preferably throughout the extent of the entire lining, and these two parts are stitched or quilted 55 together as indicated at 17.

On the outside of the layer or ply of padding is arranged a waterproof and airtight imperforate ply or strip of oil silk or its equivalent, as indicated at 18. This ply of 60 material is very soft and pliable, of minimum weight and yet serves to prevent the passage of cold air or the like through the bandage or protector, and serves therefore as the main element of the device protecting 65 the patient from danger of recurrence of pneumonia. The ply of oil silk 18 is co-extensive with the plies first mentioned and may in some instances constitute the outermost ply of the device. When it is desired 70 to be worn as an outer garment, however, the vest is preferably provided with a fabric finishing ply 19 of any suitable cloth having a dressy appearance. The edge portions of the device may be bound, stitched, 75 or otherwise so secured that all of the plies described will be maintained in proper relationship. Likewise any suitable fastening devices such as loops 20 and buttons 21 may be provided to secure the otherwise 80 open portion of the vest together.

I claim:

The herein described vest comprising an outer ply of cloth, a ply of fibrous padding, 85 a ply of lining on one side of the padding, the plies of padding and lining being permanently stitched or quilted together, and a ply of oil silk secured upon the outer side of the padding between it and the ply of cloth.

MORRIS STANGER.
